UNITED STATES PATENT OFFICE.

STEPHAN BROICHGANS, OF MILWAUKEE, WISCONSIN.

AIR-COMPRESSING APPARATUS.

SPECIFICATION forming part of Letters Patent No. 635,419, dated October 24, 1899.

Application filed October 10, 1898. Serial No. 693,102. (No model.)

To all whom it may concern:

Be it known that I, STEPHAN BROICHGANS, a citizen of the United States, and a resident of Milwaukee, in the county of Milwaukee and State of Wisconsin, have invented certain new and useful Improvements in Air-Compressing Apparatus; and I do hereby declare that the following is a full, clear, and exact description thereof.

10 My invention is especially designed for use in connection with a natural-gas supply to aerate and increase pressure of the fluid or as means for converting liquid hydrocarbon into inflammable gas under pressure; and said invention consists in certain peculiarities of construction and combination of parts constituting a simple economical automatic apparatus for compressing air and temporarily storing the product whether it be mixed with inflammable fluid or otherwise, this apparatus being hereinafter particularly described with reference to the accompanying drawing and subsequently claimed.

15 The drawing represents an elevation of my air compressing and storing apparatus, partly in section.

Referring by letter to the drawing, A represents a closed tank having a central chamber B, that rises from its bottom, the lower end of the chamber being perforated. The dimensions of the tank and chamber therein are such that space is formed between their vertical walls for a volume of water that being run into said tank through a pipe b finds its way into said chamber through the perforations at lower end of same, this chamber being provided with a vent-hole c, that permits ascent of said water to the elevation shown. Owing to a difference in height of the tank and chamber therein the water-level in one will be higher than in the other, as herein shown, and the water in the chamber is a reserve supply that compensates for loss of that outside said chamber by evaporation or otherwise.

The chamber B is provided with a central vertical tube C, open at its upper end, where it joins the otherwise closed top of said chamber, and this tube is made fast to the tank-bottom, through which it extends. As herein shown, the tube C may be screw-threaded and

have nuts run thereon against the inner and outer sides of the tank-bottom.

The upper end of tube C is provided with a guide-spider d for a rod D, and the latter extends down through a stuffing-box at the lower end of said tube. The upper end of the rod is made fast to the top of a weighted open-bottom jacket E, surrounding the chamber B in the tank A aforesaid. As a matter of detail the jacket may consist of a sheet-metal body having an inturned upper flange between a pair of metallic plates that weight said jacket, this construction being herein shown. The lower end of the rod is for connection with a motor that operates to elevate the jacket E, and, as herein shown, the motor may comprise a piston F on the lower end of said rod, a cylinder G, containing the piston, a valve mechanism controlling inlet and exhaust of fluid under pressure with respect to the cylinder, and automatic valve-shifting mechanism.

In detail the cylinder G is herein shown as having the lower end thereof in communication with a casing H, having its ends in union with an inlet-pipe I and an outlet-pipe I' for water or other fluid under pressure, it being practical to have said inlet-pipe in connection with a city water-service system. A disk J in the casing H is provided with diametrically opposite wrist-pins in connection with stems of valves K K', that control the inlet and outlet pipes pertaining to said casing. In connection with disk J, central of the same, is a weighted lever L outside of casing H, and in pivotal connection with the lever is a rod M, that extends up through a stationary guide e, this rod being provided with a vertically-adjustable beveled catch f for engagement with a hook-latch g at the lower end of another rod N in pivotal connection with the outer end of a lever P, that is fulcrumed on a bracket h, extending from the upper end of the aforesaid cylinder, a stop i being arranged to limit tilt of said lever in one direction. The inner end of the lever is provided with a longitudinal socket for a spring-controlled bevel-point slide j, operative in conjunction with a bevel-collar k on the rod D aforesaid. A link m connects the lever P (between fulcrum and outer end) with the inner end of

another weighted lever Q, and a pull-rod R, loose in a stationary guide n, connects the latch-rod N with a bell-crank S in the path of a trip-rod T in connection with a holder U, 5 hereinafter more particularly described.

Inside of tank A is a vertical flue V, extending above the water-level, and in union with the lower end of this flue is a pipe V', that depends into a water seal W, said pipe 10 being provided with an air-inlet governed by a check-valve p. Another pipe C', shown in connection with tube C, also depends into the water seal W and is provided with an air-inlet governed by a check-valve q. Leading 15 from the top of the water seal is a pipe r, that extends into a closed receptacle X and is provided with perforations adjacent to the bottom of said receptacle inside the same. A conical deflector s is arranged over the upper 20 end of pipe r and extends up through an opening in another deflector t in the upper portion of the aforesaid receptacle.

A pipe Y in union with the top of receptacle X may be part of a conduit embodying 25 the pipe Y', shown extending up into the holder U aforesaid, or these pipes may be in connection with an interposed gas and air mixing chamber or a carbureter, as circumstances may require, provision being had in 30 practice to prevent return of air or aerated gas under pressure from said holder through said conduit.

The holder U is an open-bottom shell having a central sleeve U', that surrounds a central vertical tube Z' of a tank Z, in which said shell is arranged, this tank being partially 35 filled with water.

The above-described trip-rod T has loose play in the central tubular portion Z' of tank 40 Z and is made fast to the top of holder U, pipe Y' and a distributor-pipe Y" being extended up through the bottom of said tank to an elevation above the water-line within said holder.

The parts above specified being in the arrangement shown, continued descent of the holder U to expel compressed air or aerated gas under pressure through pipe Y" will cause 45 rod T to actuate bell-crank S, whereby pull-rod R, operating on latch-rod N, will free the latter from catch f on rod M, thus permitting gravity descent of lever L (shown by dotted lines) to shift the valves K K' in the casing H, that constitutes part of the motor herein specifically set forth. The outlet-pipe I' of casing H having been closed and the inlet-pipe of said casing opened by shift of valves K K', the inflow of fluid under pressure will 50 be exerted on piston F to elevate the jacket E in the tank A of the apparatus. As this jacket moves up it displaces air in tank A and forces this air out through the flue V and pipe V' into the water seal W, from which it escapes into receptacle X to pass on through pipe Y, condensation of excess moisture deflected and caught in said receptacle finding 55 its way back through the perforations of pipe r into said water seal. In the meantime air

is drawn in through the valve-controlled inlet of pipe C' by the suction exerted on the part of the aforesaid jacket, and upon ascent of 70 the rod D the bevel-collar k thereon operates against slide j to tilt levers P Q, as shown by dotted lines, this tilt permitting a reengagement of the latch-rod with the catch f, as is also shown by dotted lines. The rod-collar 75 k having passed away from the slide j, there will be automatic reverse tilt of lever Q to cause a return of levers L P and parts in connection therewith to original position, whereby the valves K K' are again shifted to close 80 the inlet and open the outlet pipes of the cylinder G, whereby the piston F in said cylinder is free to descend under the weight of the aforesaid jacket, the air previously drawn into the latter being forced out through tube 85 C and pipe C' into the water seal W, from whence it escapes through receptacle X and pipe Y free of excess moisture. Descent of jacket E exerts a suction that draws air in through the valve-controlled inlet of pipe V' 90 to fill tank A above its water-level.

Incidental to reciprocation of jacket E air or aerated gas is forced through pipe Y' into holder U, and ascent of the latter causes lift of trip-rod T away from bell-crank S previous 95 to the time that rod-collar k operates against slide j on upstroke of the aforesaid piston. On descent of the piston the rod-collar operating against slide j retracts the latter and is thus afforded clearance.

Having thus described my invention, what I claim as new, and desire to secure by Letters Patent, is—

1. An air-compressing apparatus comprising a closed tank provided with a liquid-inlet, 105 an air-conduit open to the tank above the liquid-level therein but provided with an air-inlet outside of said tank governed by a check-valve, a central chamber rising from the tank-bottom but provided with perforations at its lower end, another air-conduit having open-end union with the otherwise closed top of the chamber and provided outside the aforesaid tank with an air-inlet governed by a check-valve, an open-bottom jacket surrounding 115 said chamber, and means for reciprocating the jacket.

2. An air-compressing apparatus comprising a closed tank provided with a liquid-inlet, 120 an air-conduit open to the tank above the liquid-level therein but provided with an air-inlet outside of said tank governed by a check-valve, a central chamber rising from the tank-bottom but provided with perforations at its lower end, another air-conduit having open-end union with the otherwise closed top of the chamber and provided outside the aforesaid tank with an air-inlet governed by a check-valve, an open-bottom jacket surrounding 125 said chamber, means for reciprocating the jacket, and a reciprocative holder having communication with the air-conduits and a distributor-pipe.

3. An air-forcing mechanism, a reciproca-

- tive holder consisting of an open-bottom shell in a tank partially filled with liquid and provided with a central vertical tube, supply and distributer pipes extending through the tank-bottom to an elevation above the liquid-level within the shell, a sleeve central of said shell surrounding the tank-tube, a rod depending from the top of the shell-top and guided in said tank-tube, a fluid-pressure motor having a piston in rod connection with the air-forcing mechanism, valves controlling the inlet and discharge of the motor, and valve-shifting mechanism operative in conjunction with the rod depending from the aforesaid shell.
- 5 4. An air-compressing mechanism comprising a closed tank provided with a liquid-inlet, an air-conduit open to the tank above the liquid-level therein, but provided with an air-inlet outside of said tank governed by a check-valve, a central chamber rising from the tank-bottom but provided with perforations at its lower end, another air-conduit having open-end union with the otherwise closed top of the chamber and provided outside the aforesaid tank with an air-inlet governed by a check-valve, an open-bottom weighted jacket surrounding said chamber, a cylinder having valve-controlled inlet and outlet for a fluid under pressure, a piston in the cylinder, a rod connecting the jacket and piston, a reciprocative holder in communication with the air-conduits and a distributer-pipe, and a valve-shifting mechanism operative in conjunction with the piston-rod and said holder.
- 20 5. An air-compressing apparatus comprising a motor consisting of a cylinder provided with valve-controlled inlet and outlet for fluid under pressure, a piston in the cylinder, having rod connection with a reciprocative ele-

ment of the apparatus, and a mechanism consisting of a weighted lever in connection with the valves, a vertical lift-rod in pivotal connection with said lever, a catch on the rod, another lever provided at one end with spring-controlled slide, a collar on the piston-rod co-operative with the slide, a latch-rod in connection with the latter lever for engagement with said catch, a weighted lever linked to the one provided with said slide, a pull-rod engaging the latch-rod, a bell-crank in connection with the pull-rod, and a trip-rod for the bell-crank depending from a reciprocative holder for the compressed air.

40 6. An air-forcing mechanism comprising a closed tank provided with a liquid-inlet, an air-conduit open to the tank above the liquid-level therein but provided with an outside air-inlet governed by a check-valve, a chamber rising from the tank-bottom but provided with perforations at its lower end; another air-conduit having open-end union with the otherwise closed top of the chamber and provided with an outside air-inlet governed by a check-valve, an open-bottom jacket surrounding said chamber, a cylinder having valve-controlled inlet and outlet for a fluid under pressure, a piston in the cylinder in rod connection with said jacket, and valve-shifting mechanism operative in conjunction with a reciprocative element of the apparatus.

45 7. In testimony that I claim the foregoing I have hereunto set my hand, at Milwaukee, in the county of Milwaukee and State of Wisconsin, in the presence of two witnesses.
